Howard E. Smith

ATTORNEY.

UNITED STATES PATENT OFFICE.

ERNEST M. REYNOLDS, OF CLEVELAND, OHIO.

COUPLER FOR RADIORECEPTION.

Application filed May 15, 1922. Serial No. 560,930.

To all whom it may concern:

Be it known that I, ERNEST M. REYNOLDS, a citizen of the United States, residing at Cleveland, in the county of Cuyahoga and State of Ohio, have invented a certain new and useful Improvement in Couplers for Radioreception, of which the following is a full, clear, and exact description, reference being had to the accompanying drawings.

10 This invention relates to the art of radio signaling or wireless communication and has especial reference to wireless telephoning although it is not necessarily confined thereto. The objects of the invention are 15 the provision of an improved type of variable inductance by which the receiving circuit can be brought into resonance with the incoming impulses with ease, accuracy, and celerity; the provision of a variable resistance having a sharp and definite action whereby incoming wave lengths may be 20 analyzed with accuracy and those excluded which are not desired; the provision of a coupler of great simplicity, compactness, 25 convenience and cheapness; while further objects and advantages will become apparent as the description proceeds.

In the drawings accompanying and forming a part of this application I have shown 30 one form of apparatus in which my invention may be embodied together with two modes of attaching it in circuit, although it will be understood that changes may be made both in construction and installation.

35 In these drawings Fig. 1 is a diagrammatic layout of a complete receiving set of the crystal detector type equipped with my improved coupler; Fig. 2 is a diagrammatic layout of a partial receiving set of the 40 audion bulb type, showing the mode of employing my coupler; Fig. 3 is a perspective view of my coupler taken from the rear; Fig. 4 is a front elevation and Fig. 5 a top plan view of the same.

45 Describing the parts by reference characters, 1 represents an exteriorly rectangular frame of insulating material having a central cavity 2, and 3 represents a primary winding thereon. When made of wood the frame is merely hollowed out to form a semi-circular cavity terminating short of the opposite end of the frame, the two ends of the U thus produced being connected by bars 4, 4 of insulating material such as 50 wood or, preferably, vulcanite. Pivoted in these bars is a semi annular core 5 of insulating material, such as wood, on which is wound the secondary coil 6. The ends of this core are connected by a member 7 of insulating material in opposite sides of which are inserted the pivot pins 8, 9, one of which carries the knob 10. The ends of the secondary are attached to these pivot pins and contact is made by strips 11, 12 carried by the bars 4 and engaging the respective pins. The ends of the primary winding are attached to suitable binding posts 13 and 14.

The secondary winding thus consists essentially of a wire helix, curved longitudinally and mounted for rotation about its center of curvature. This axis is also transverse to the axis of the primary coil which is made of oblong rectangular shape with its minimum dimension parallel to the pivot axis and its maximum dimension radially thereof, this minimum dimension being only slightly greater than the diameter of the helix and the maximum dimension being sufficient to take both ends of the helix at once. It will be understood that by "helix" I do not confine myself to a cylindrical coil; indeed I have shown it as flat sided: and by "arcuate" I mean to include either semi-circular as shown or more or less than that. I find it most convenient to locate the pivot axis substantially at one end of the primary coil, but I do not limit myself exactly thereto.

To one of the bars 4 I secure an insulating panel 15 which overhangs the primary wires at a little distance and carries a plurality of contact points 16, arranged in an arc of a circle so as to be contacted by the pivoted arm 17 affixed to the knob 18 and connected to the binding post 19. The contact points are tapped onto the primary at suitable intervals. As an example of a balance which I have found very satisfactory, I have employed a primary coil of eighty turns connected to the contact points at every eighth turn, in combination with a secondary having one hundred and thirty two turns, the former of No. 22 and the latter of No. 24 single cotton covered copper wire. Of course I do not limit myself to this number of turns, or size of wire or shape of parts.

I also show two modes of connecting my

improved coupler in circuit; I lay no claim to either circuit as such, nor do I limit my improved variable inductance apparatus to these particular circuits, but show them only to enable a better understanding of the nature and mode of using my invention.

Referring to Fig. 1, the aerial 20 is connected to one end of the primary coil as by the binding post 18, the contact finger 17 being grounded via the binding post 19. The two ends of the secondary are connected to the poles of a telephone receiver 21, the two sides of the secondary circuit being bridged at spaced points by a variable condenser 22 and a second condenser 23 which may or may not be variable, and one side of this secondary circuit having a crystal detector 24 interposed therein between the two condensers. This is one mode of connecting my improved coupler in a crystal type of receiving circuit.

If it be desired to employ the same in circuit with a detector tube, one of the arrangements which may successfully be employed is shown in Fig. 2, wherein 3 represents the primary winding which is connected as shown in Fig. 1, and 6 represents the secondary. One end of the secondary is connected to one pole of a variable condenser 25, to one of the legs of the lamp filament 26, and one terminal of the telephone receiver 27; the other end of the secondary is connected to the opposite pole of the condenser 25 and to one pole of a second condenser 28, the other pole of which is connected to one of the detector terminals of the induction tube, such as the grid 29. The remaining terminals of the tube, in this case the plate 30, is connected to the remaining terminal of the telephone receiver through the battery 31 which is generally of comparatively high voltage, and across the two legs of the lamp filament 26 is attached a second battery 32 which is generally of much lower voltage and is provided with a variable resistance 33.

In either circuit, or any other successful circuit in which my improved coupler may be employed, the method of tuning is the same as that followed with other types of variable inductance, namely that the number of turns of primary, the angular position of the secondary, and the capacity in circuit therewith are mutually adjusted until the condition of resonance exists in the secondary circuit which corresponds to the wave length of the signals sought to be received. The main advantages of my improved coupler are the close relation of the primary and secondary which produces induced currents of greater strength and the fact that the adjustment follows approximately a linear law rather than a sine curve which causes the adjustment ratio to be substantially uniform throughout the entire

range of adjustment of the secondary. As a result of these two conditions the tuning becomes very accurate, and enables the selective reception of signals which vary by comparatively narrow wave lengths and also to the elimination of wireless and static interference to a very high degree.

It will be understood, however, that I do not restrict myself to the exact designs herein shown, nor to any specified number of turns of wire, nor to the particular circuits herein illustrated, nor in any other way except as specifically recited in my claims.

Having thus described my invention what I claim is:

1. A variable inductance apparatus for radio receiving sets comprising a rectangular coil which forms the primary winding and a helical coil which forms the secondary, said helical coil being curved longitudinally to arcuate form and mounted for rotation about an axis which is perpendicular to the axis of the first named coil and concentric to the curvature of the helix.

2. A variable inductance apparatus for radio receiving sets comprising an oblong rectangular primary coil and an elongated helical secondary coil which is curved into arcuate shape, the diameter of the helix being less than the smallest dimension and the diameter of its curvature being less than the largest dimension of said primary coil, and means adjustably pivoting said secondary coil upon an axis which is parallel to the smallest dimension of the primary and concentric with the curvature of the secondary.

3. A variable inductance apparatus for radio receiving sets, comprising a helical secondary curved to arcuate shape and mounted for adjustment about its axis of curvature, in combination with a primary coil of a size to receive both ends of the secondary simultaneously.

4. In a device of the character described, in combination, a rectangular frame, an arcuate core pivoted in said frame upon an axis which is concentric with its own curvature and lies in the plane of the frame, a primary winding located at one side of said frame with its axis perpendicular to said pivot axis, and a secondary coil wound on said arcuate core.

5. In a device of the character described, in combination, a rectangular frame, a cross piece pivoted therein, an arcuate core carried thereby, a winding thereon, and a primary winding carried by said frame.

6. In a radio coupler, a rectangular coil, a panel parallel to one side thereof, a plurality of contact points carried by said panel and tapped into intermediate portions of said coil, a movable contact finger for said points, and a helical secondary curved to arcuate form and movably supported in

- side the first coil upon an axis which coincides with the axis of the arc defined by such secondary coil and intersects perpendicularly the axis of said first coil.
6. 7. In a radio coupler, in combination, a rectangular primary coil, and an approximately torus-shaped secondary coil adjustably pivoted therein about the axis of the torus.
10. 8. In a radio coupler, in combination, a flat sided primary coil, and an approximately helical secondary coil having its axis curved to conform substantially to the arc of a circle whose axis intersects such flat sides.
9. In a radio coupler, in combination, a primary coil having flat sides built up of a plurality of turns of wire and a flat sided secondary coil pivoted inside said primary
20. 20. coil upon an axis which is normal to said flat sides, said primary coil having a plurality of taps arranged at different points and a connection for said taps.
28. 10. In a radio coupler, in combination, a primary coil having flat sides, and a helical secondary coil curved into arcuate form and fitting closely between such flat sides, said
- secondary being adjustable about an axis which is normal to said flat sides.
11. In a radio coupler, in combination, a rectangular primary coil comprising a plurality of successive turns of wire, a plurality of taps connected to said turns at spaced points, a connection for said taps whereby a greater or smaller portion of said coil can be thrown into circuit, and a secondary coil shaped approximately like the segment of a torus adjustably pivoted therein upon an axis perpendicular to such flat sides.
12. In a radio coupler, in combination, a flat sides primary coil consisting of a plurality of turns a plurality of taps connected thereto at spaced points, a connection for said taps whereby a greater or smaller portion of said coil can be thrown into circuit, and an approximately helical secondary coil having its axis curved to conform substantially to the arc of a circle whose axis intersects said flat sides, said secondary coil being adjustable about such axis.

In testimony whereof, I hereunto affix my signature.

ERNEST M. REYNOLDS.
